CURRENT REGULATOR TUBE

Clarke C. Minter, Washington, D. C.

Application January 28, 1957, Serial No. 636,841.

11 Claims. (Cl. 201—63)

(Granted under Title 35, U. S. Code (1952), sec. 266)

The invention described herein may be manufactured and used by or for the Government of the United States of America for governmental purposes without the payment of any royalties thereon or therefor.

The present invention relates to current regulating devices and more particularly to a ballast tube for automatic regulation of current with minimum lag and hysteresis.

Formerly ballast tubes have been used to maintain a constant current for a changing voltage source in which the range of regulation is satisfactory but there is substantial time lag in attaining current stabilization for any change in voltage. The tubes of the prior art usually consist of a small iron wire filament mounted in a sealed glass containing hydrogen at a suitable low pressure. Ballasting action is not limited to the above combination, since other tubes have been made by a combination of other metal filaments and other gases, however, the iron-hydrogen combination is the most used and best results have been obtained from this combination.

In order to have ballasting action the metallic filament must have a high temperature coefficient of resistance that increases with temperature such that the resistance of the filament increases more rapidly than the temperature as it is heated. When there is an increase in voltage across the filament, the wire filament of the tube is heated thereby raising the resistance thereof to electrically account for the increase in voltage, that is, the increase in voltage is converted by the filament of the ballast tube into resistance rather than being divided across the other portions of the circuit, thereby keeping the current constant.

In order for ballasting to occur, temperature and resistance differences must exist in the portion of the current heated filament to cause hot-spots, these differences are brought about by (1) local differences in the diameter of the wire and (2) cooling effect of the supports holding the filament. In the straight filament type ballast tube in which local differences occur, diameter differences of the filament cause ballasting by creation of hot-spots at the nonuniform points. The ballasting action of different tubes vary since the wire filaments are not uniformly made and the ballasting action is only for a short range of voltage difference. Due to the cooling of the filament by the supports there is substantial time lag before the current becomes steady after a change in voltage.

In the prior art ballast tubes, not only is there a time lag in current stabilization after a change in voltage but the ballasting is not the same for a decreasing voltage as it is for an increasing voltage. When ballasting is not the same in each direction, hysteresis is introduced and affects the operation of the tube.

It is therefore an object of the present invention to provide a ballast tube which reduces the time lag in voltage adjustments in a ballast tube.

Another object is to provide a ballast tube which reduces hysteresis to a minimum so that current regulation

2

is the same for a decreasing voltage as it is for an increasing voltage.

Yet another object is to provide a ballast tube which will provide ballasting action over a wide range of voltage change.

Still another object is to provide a ballasting tube having non-uniform heating in an isolated filament of uniform diameter.

Other and more specific objects of this invention will become apparent upon a more careful consideration of the following detailed description when taken together with the drawings, in which:

Fig. 1 is a cross-sectional view of one embodiment of this invention illustrating the relative parts; and

Fig. 2 is a cross-sectional view of a modification of Fig. 1.

In accordance to the present invention ballast action is provided by positioning a filament of substantially perfect uniform diameter made of a metal having a high temperature coefficient of resistance which increases with an increase in temperature within an envelope structure which has portions of the wall structure at varying distances from the filament. The filament is supported by a spring at one end thereof to allow for expansion and contraction of the filament and to provide a means for maintaining the filament centrally along the axis of the envelope.

With particular reference to the drawings wherein like reference characters represent like parts throughout, there is shown in Fig. 1 one modification of a ballast tube 10 provided with a glass or metal jacket 11 within which is positioned a double conical envelope 12 of glass or metal wall structure joined at their bases and secured at each end 13 and 14 to the inside of the jacket. A material of substantially perfect uniform diameter having a high temperature coefficient of resistance such as a tungsten wire filament 15 or any other suitable material is positioned along the longitudinal axis of the envelope 12 of metal wall structure and connected at one end to a lead wire 16 and connected at the opposite end to a spring 17 which is connected to a second lead wire 18. The spring serves as a means for maintaining the filament in axial alignment within the tube. The double conical envelope is filled with a suitable gas such as hydrogen at any suitable low pressure.

The ballast tube can be air-cooled or water cooled and for this purpose the double conical envelope 12 is shown surrounded by the jacket 11. If desired, the tube can be constructed without the jacket 11 and in this case the envelope 12 will be closed at the ends thereof and the lead wires 16 and 18 must be insulated therefrom.

In operation of the modification shown in Fig. 1, the tube is positioned in a circuit having a desired variable voltage source. When a voltage drop is applied across the filament 15, the filament heats-up due to the current flow and the resistance of the wire changes as the wire heats-up. The double conical envelope 12 having a varying distance from the filament will tend to absorb heat more readily from the ends of the filament than at the midpoint thereof thus causing the filament to develop a hot-spot at its midpoint. This hot-spot provides the ballasting action for the tube and as the current momentarily increases by increasing the voltage across the filament, the filament gets hotter raising the resistance thereof from the midpoint toward the ends which stabilizes the current. The varying distance of the envelope from the filament absorbs heat from the filament according to the distance between the filament and the wall surface and therefore causes the filament to heat more readily from the midpoint towards the ends to provide a constant current for the circuit over a limited voltage range due to

the change in resistance of the filament as the filament heats-up.

In reference to Fig. 2, there is shown a modification of Fig. 1 which has essentially all the elements of Fig. 1. As shown, the envelope wall structure 21 is made of glass or metal having end surfaces 22 and 23 of equal diameter between which is formed wall sections 24, 25, 26, 27 and 28. Sections 25 and 27 are cylindrical sections equal in diameter to the end sections whereas sections 24, 26, and 28 are of spherical shape, each having a different radii formed successively with a decreased radii from one end of the structure toward the other. Lead wires 16 and 18 are insulated from the wall surface at 31 and 32 such that the filament is positioned longitudinally along the axis of envelope 21.

The structure of Fig. 2 provides a plurality of hot-spots as the voltage drop is increased across the filament and functions similar to the operation of Fig. 1. A hot-spot is produced first in the spherical section having the greatest radius since the wall surface is farthest from the filament. As the voltage drop is increased hot-spots will develop successively along the filament within the spherical section having the next longest radii until the voltage drop is great enough to develop hot-spots at all of the spherical surfaces of different radii. Each hot-spot developed produces greater filament resistance thereby permitting a ballast action for a greater variance of voltage.

The modification as shown in Fig. 2 will provide ballast action over a much greater range than the modification of Fig. 1 and can also be provided with an envelope for water-cooling the envelope as shown in the modification of Fig. 1.

For the purposes of this invention tungsten is desired as the filament material since tungsten is the strongest of the desired metals and can be made more easily into a filament of substantially perfect uniform diameter. However the invention is not limited to filaments of tungsten wire since it is obvious that any desired metal of uniform diameter can be used. As an example, the tubes can be made with a one mil tungsten wire filament approximately seven inches long secured in an envelope filled with hydrogen to a pressure of about five millimeters of mercury.

The construction of the above described modifications of different ballast tubes will control the current for a decreasing voltage as well as for an increasing voltage. Due to the construction of the tube, gradual absorption or release of heat by the wall structure causes an increase or decrease in the resistance of the filament and controls the current across the filament such that there is very little time lag in stabilizing the current across the devices in the circuit in which the ballast tube is connected.

Obviously many modifications and variations of the present invention are possible in the light of the above teaching. It is therefore to be understood, that within the scope of the appended claims, the invention may be practiced otherwise than as specifically described.

What is claimed is:

1. A current regulating tube comprising an elongated envelope containing hydrogen gas, a pair of support leads extending from said envelope, a straight elongated resistance wire filament having a uniform diameter and made of material having a high temperature coefficient of resistance that increases with temperature positioned longitudinally along the axis of said envelope, said filament being connected between said support leads, the surface of said envelope directly opposite said filament having portions of the surface thereof at greater distances from said filament than the distance between the ends of said envelope and said support leads, and means for maintaining said filament in axial alignment within said envelope.

2. A current regulating tube comprising an elongated

envelope containing hydrogen gas, a pair of support leads extending from said envelope, a straight elongated resistance wire filament having a uniform diameter and made of material having a high temperature coefficient of resistance that increases with temperature positioned longitudinally along the axis of said envelope, said filament being connected to and between said support leads, spring means for maintaining said filament in axial alignment within said envelope, and, the surface of said elongated envelope directly opposite said filament having portions of the surface thereof at greater radii from said filament than the distance between the ends of said envelope and said support leads.

3. A current regulating tube comprising an elongated envelope containing hydrogen, a pair of lead supports extending from the ends of said envelope along the axis thereof, a straight elongated resistance wire filament of material having a high temperature coefficient of resistance that increases with temperature and of uniform diameter positioned longitudinally along the axis of said envelope, said filament being connected to and between said lead supports, spring means connected to and between one end of said filament and one of said supports for maintaining said filament in axial alignment within said envelope, the surface of said elongated envelope directly opposite said filament being constructed with portions thereof at different radii from said filament than the distance between the ends of said envelope and said support leads.

4. A current regulating tube comprising an elongated double conical envelope containing hydrogen gas, a pair of lead supports extending from said envelope along the axis thereof, a straight elongated resistance wire filament of material having a high temperature coefficient of resistance that increases with temperature positioned along the longitudinal axis of said envelope, said filament being connected to and between said support leads, means for maintaining said filament in axial alignment within said envelope, said double conical envelope having its greatest diameter opposite the midpoint of said filament.

5. A current regulating tube as claimed in claim 4 wherein said resistance wire filament is of uniform diameter.

6. A current regulating tube as claimed in claim 5 wherein the envelope is made of metal.

7. A current regulating tube as claimed in claim 5 wherein said means for maintaining said filament in axial alignment within said envelope is a spring of larger diameter wire than said filament and positioned between one end of said filament and the end of one of said lead supports.

8. A current regulating tube comprising an elongated envelope containing hydrogen gas, the surface of said envelope being formed by equally spaced spherical portions each having different radii and positioned between portions extending from the ends of said envelope along the axis thereof, a resistance wire filament of material having a high temperature coefficient of resistance that increases with resistance positioned along the longitudinal axis of said envelope, said filament being connected to and between said lead supports, and means for maintaining said filament in axial alignment within said envelope.

9. A current regulating tube as claimed in claim 8 wherein said resistance filament wire is of uniform diameter.

10. A current regulating tube as claimed in claim 8 wherein the radii of each successive spherical portion is less than the preceding spherical portion.

11. A current regulating tube as claimed in claim 8 wherein said means for maintaining said filament in axial alignment within said envelope is a spring of larger diameter wire than said filament and positioned between

one end of said filament and the end of one of said lead supports.
